UNITED STATES PATENT OFFICE.

EMIL L. CLAUS, OF MILWAUKEE, WISCONSIN, ASSIGNOR, BY DIRECT AND MESNE ASSIGNMENTS, TO MILWAUKEE GAS SPECIALTY COMPANY, OF MILWAUKEE, WISCONSIN, A CORPORATION OF WISCONSIN.

OVEN-HEAT REGULATOR.

Application filed November 10, 1923. Serial No. 673,953.

This invention relates to certain new and useful improvements in oven heat regulators capable of use on kitchen stoves, ranges and any other device where it is desired to maintain a predetermined degree of heat in a compartment such as an oven or any other space.

Various types of oven regulators have been designed and are on the market and while they apparently function to some degree of certainty and accuracy, they are objectionable from the stove manufacturers standpoint in that they require special piping and fittings, materially increasing the cost of installation, and furthermore they are difficult to install on gas stoves not arranged for their installation at the time of manufacture.

Having this in mind, it is an object of my invention to provide an oven heat regulator which eliminates the necessity of providing special piping and fittings materially simplifying its application to an oven or other chamber or compartment to be regulated, reducing the time, labor and material required, and facilitating its ready application to stoves now in use or to stoves at the time of their manufacture.

Another feature which is objectionable in the oven heat regulators now on the market is that they are not designed to meet all stove construction, and it is, therefore, another object of this invention to provide an oven heat regulator which is capable of application to all types of stoves without requiring special fittings or arrangements.

Another feature which is objectionable in the types of oven heat regulators now on the market is that special crating must be provided for the shipment of the stove so equipped in that they project or protrude from the oven and means must be provided to properly accommodate and protect the same.

This invention, therefore, contemplates as another of its objects to provide a thermostatic instrument which does not protrude from the oven beyond the stringer of the stove, which is accommodated in the standard crates of the various manufacturers and, therefore, the requirement of special crating is eliminated.

A further objection to the types of oven heat regulators now on the market is that the gas has contact with the oven, opening

the device to serious objections on the part of the stove manufacturers, the users and the fire underwriters, and this invention has for another of its objects to provide an oven heat regulator in which the gas is absolutely disconnected from the oven, thus insuring an increased factor of safety in the operation thereof and eliminating the necessity of snug fittings and packing glands such as are necessary with the other devices in order to reduce the possibility of the gas passing into the oven to a minimum.

Another objectionable feature of the thermostatic devices of the character described now on the market is that they employ one or more springs acting against a thermostatic member which has many disadvantages in that after continued use, the spring crystallizes and loses its strength throwing the instrument out as far as accuracy is concerned and furthermore the spring is generally affected by the heat of the oven resulting in a serious loss in efficiency.

Having this objection to the spring in mind, this invention contemplates as another object the provision of two members co-acting against each other to provide a positive movement of the control valve to and from open position to thus materially increase the efficiency and positiveness of operation of the instrument.

Another object of this invention resides in the provision of a thermostatic member having a high co-efficient of expansion and located within the oven to be influenced by the heat therein and acting against a member having a low co-efficient of expansion and located outwardly of the oven within a neutral zone whereby the positiveness of the operation of the device is increased.

Another object of this invention resides in the provision of means permitting the circulation of air through the thermostatic member having a high co-efficient of expansion, whereby the same quickly responds to changes in temperature to thus increase the sensitiveness of the instrument.

Another object of this invention is to provide means for circulating air through the member having a low co-efficient of expansion to prevent its being influenced by heat radiated from the oven and to thus increase the efficiency and accuracy of the instrument.

Another object of this invention resides in the provision of a rotatable actuating dial requiring but one turn or less to adjust the instrument from minimum to maximum heat.

5 Another object of this invention resides in the provision of a device having a compound dial whereby the regulator may be adapted for use with either artificial or natural gas without requiring any change in the construction thereof.

10 Another object of this invention resides in the provision of a device, the thermostatic member of which works against the solid 15 cast iron front of the oven to thus insure accuracy of operation.

In thermostatic instruments for controlling oven temperatures, it is essential that an adjustable pilot light be provided and 20 heretofore considerable difficulty has been experienced in that the adjustment for the pilot light has been from a remote point resulting in frequent extinction of the pilot inasmuch as the gas pressure is reduced by 25 expansion in the pilot supply tube or pipe and it is, therefore, another object of this invention to provide an improved pilot structure wherein the adjustment of the volume of gas supplied thereto is made at the 30 pilot tube.

Another object of this invention resides in the provision of a pilot light having means located at the pilot tip, but operable from a remote point, for adjusting the pilot 35 light.

Another object of this invention resides in the provision of a valve structure including telescoping tube members actuated from a thermostatic member influenced by the 40 oven temperature, whereby the necessity of a snug leak-proof fit between the valve members is eliminated and, consequently, the necessity of lubricating the parts and the occurrence of sticking avoided.

45 It is another object of this invention to provide a thermostatic instrument for regulating the temperature of an oven having several means of adjustment all of which are in convenient places exteriorly of the stove 50 where atmospheric conditions prevail whereby the adjustments are not influenced in any manner by the oven heat.

Another object of this invention resides in the provision of a device of the character 55 described wherein the action of the member influenced by the oven heat is direct, whereas, in other instruments of this character now on the market, the thermostatic member works on the valve in a ratio of approximately one to fifty.

60 Another object of this invention resides in the provision of a thermostatic instrument for regulating the temperature of an oven in which it is unnecessary to penetrate the oven 65 side walls thus eliminating the consequent

increase in losses due to cracking of the enamel such as is encountered in the manufacture of stoves where it is necessary that the side oven panels be penetrated in order to permit the instrument to enter the oven.

The prerequisites for a thermostatic instrument to meet all prevailing conditions are accuracy, maintenance, economy and safety, and it is a further object of this invention to provide an instrument of the character described in which all of these essential features are incorporated.

A still further object of this invention resides in the provision of a device which has provision for horizontal, vertical and universal adjustment between it and the shut-off cock for the oven whereby the device may be readily adapted to any stove irrespective of the relation of the oven to the oven control valve.

80 And a still further object of this invention resides in the provision of a device of the character described wherein the drilling of only a small hole in the front and rear oven walls and the substitution of a special valve 85 for the conventional oven shut-off cock is required for its application to any make of oven.

86 With the above and other objects in view which will appear as the description proceeds, my invention resides in the novel construction, combination and arrangement of parts substantially as hereinafter described and more particularly defined by the appended claims, it being understood that such 91 changes in the precise embodiment of the hereindisclosed invention may be made as come within the scope of the claims.

In the accompanying drawings, I have illustrated one complete example of the physical embodiment of my invention, and a modification thereof, constructed according to the best modes I have so far devised for the practical application of the principles thereof, and in which:

Figure 1 is a perspective view of a portion of a gas stove or range illustrating the application thereto of an oven heat regulator embodying this invention;

Figure 2 is a side view of the controlling valve looking in the plane of the line 2-2 of Figure 3, the medial portion thereof being broken away, and but a portion of the oven front frame being illustrated;

Figure 3 is a sectional view taken vertically through the valve structure at right angles to Figure 2 on the plane of the line 3-3 thereof;

Figure 4 is a detail view, partly in vertical section and partly in elevation, of the lower portion of the control valve, said view being taken through Figure 7 on the plane of the line 4-4;

Figure 5 is a view in top plan illustrating the thermostatic members for actuating my

device, the medial portion thereof being broken away and the oven wall and the guard or covering for the forward ends of said members being in section;

5 Figure 6 is a detail view of the adjustable pilot for the oven burner, said view being partly in section and partly in side elevation, and taken through Figure 3 on the plane of the line 6—6;

10 Figure 7 is a view, partly in section and partly in top plan, taken through Figure 2 on the plane of the line 7—7;

15 Figure 8 is a detail sectional view illustrating the by-pass for insuring the maintenance of a minimum flame at the oven burner, said view being taken through Figure 7 on the plane of the line 8—8;

20 Figure 9 is a fragmentary sectional view taken on the plane of the line 9—9 of Figure 7, and

25 Figure 10 is a view similar to Figure 2 with the lower portion thereof broken away and in section and illustrating a slightly modified construction of valve in which a reciprocal sleeve is employed in lieu of the rotating sleeve of that embodiment illustrated in Figures 1 to 8, inclusive.

30 Referring now more particularly to the accompanying drawings, in which like numerals designate like parts throughout the several views, the numeral 10 designates a heating oven which is provided at its front with the usual door 11 communicating with the space 12 or oven proper, the oven may be 35 of either the single or double wall type and has a front frame 13 surrounding the opening closed by the door 11 and which is of sturdy material, such as cast iron, steel or the like, and extends along the top sides and 40 bottom of the oven door opening and is suitably connected with the frame work 14 of the range proper. The oven is heated by a burner 15, illustrated by dotted lines in Figure 1, of any desired design or construction 45 and connected with a stringer pipe 16, mounted at the forward portion of the frame 14, through a gas cock 17, to be later more specifically described, and a manifold 18.

50 The rigid frame-work 13 of the oven is of such construction as to have practically no contraction or expansion under the ranges of temperature at which the ordinary oven is operated and on this frame-work my improved oven heat regulator or instrument is 55 mounted. The upper, inner corner of the frame-work has a small opening or aperture 19 therein through which the forward short end 20 of a tubular thermostatic member 21 having a relatively high co-efficient of expansion projects, the rear end 22 of said member being projected outwardly through an opening 23 in the rear oven wall. The forward end 20 of member 21 is rigidly secured to the frame 13 by a pair of clamp 60 nuts 24 engaging the opposite sides thereof

whereby the expansion or contraction of the member 21 under influence of temperature changes in the oven increases or decreases the distance between the frame 13 and the end 22 of the member 21.

70 A cap or bearing member 25 is threaded on the end 20 and mounts the upper end of a trunnion 26 closing the outer end of a sleeve valve member 27. The valve member 27 is preferably tubular and has its upper 75 portion rotatably journaled in a cap 28 closing the upper end of a housing 29, the lower end of which is threaded in a base member 30 in register with a recess 31 therein. The lower end of the valve member 27 80 is disposed in the recess 31 and is rotatable over a normally stationary valve member 32 which is adjustably mounted in the base member. The valve members 27 and 32 are provided with complementary ports or openings 85 33 and 34, respectively, adapted to align and disalign upon rotation of the member 27, in the manner hereinafter described.

80 The base member 30 is firmly secured to the frame-work 13 by a strap or bracket 90 member 35, see Figures 1, 2, 3, 7 and 10, whereby the unit is rigidly secured to the frame-work of the oven by the members 25 and 35 with the rear ends of the members 21 and 36 free of the oven.

95 As will be readily obvious the member 21 is influenced by the heat within the oven 12 and expands or contracts as the oven temperature raises or falls and this contraction or expansion is imparted to the valve member 27 through a member 36 having a relatively low co-efficient of expansion and to which the member 21 has its end 22 firmly secured by a connecting member 37. The member 36 is preferably disposed outwardly 100 of the oven in a neutral zone and out of the range of the influence of the oven heat and has its forward end 38 directed inwardly and flattened, as at 39, for pivotal connection between the adjacent bifurcations of a 105 crank member 40 by a removable pivot pin 41. The crank 40 is fixed to the trunnion 26 and has two complementary ends to permit the application of the instrument to either a right or left hand oven without requiring 110 special parts.

115 The forward end of member 21 being made fast to the rigid frame 13 of the oven and the rear end thereof being rigidly connected with the member 36, converts the longitudinal contraction and expansion of the member 21 to rotary motion at the valve member 27, aligning and disaligning the ports 33 and 34 to vary the volume of gas flowing therethrough, as hereinafter described.

120 The member 30 is provided with a central bore or well 41 in the upper end thereof communicating with recess 31 and a recess 42 in the lower portion of the base member.

The bore 41 is preferably tapered and receives the lower tapered portion 43 of the valve member 32, the extreme lower end of which passes outwardly through the member 30, and has a clamp or collar member 44 secured thereto which secures the member 32 in the bore 41.

The collar member 44 is adjustable on the extended end 45 of the member 32, being split, as at 46, and provided with a clamp bolt 47. The tapered portion 43 of valve member 32 is yieldably secured in the bore 41, while the collar 44 is loose on the extension 45 and being adjusted, by a spring 48 confined between a washer 49 secured to the extreme lower end of the member 32 by a screw 50 and the collar member. The upper face of the collar member is preferably counter-bored to receive a circular boss or 20 enlarged portion 51 on the under-face of the base member.

The gas cock 17 is of special construction, the gas instead of flowing directly from the stringer 16 to the manifold 18, flows first 25 through the control valve hereinbefore described, thence back through the gas cock and into the manifold. This is accomplished by providing the gas cock with auxiliary outlet and inlet ports 52 and 53 respectively, whereby movement of the gas cock plug 54 by its handle 55 to open position registers the port 52 with the stringer 16 and the port 53 with the manifold 18. The auxiliary outlet port 52 has a coupling tube 56 connected therewith, in which one end of an extensible tube 57 is telescoped and adjustably secured therein by a binding cap or head 58 threaded over the end of tube 56. The head 58 has a port 58' adapted to ride over the 40 outer tapered end 59 of the tube 57 to secure the same in adjusted position in tube 56 to prevent the leakage of gas therewith. The other end of tube 57 is adjustably telescoped in one end of an L-coupling 60 and adjustably secured therein by a head 58 and the other end of the L-coupling has one end of a tube similar to the tube 57 adjustably telescoped therein, the other end of which is adjustably telescoped in a coupling 61 communicating with the recess 42, said second tube 57 having its ends adjustably secured in the couplings 60 and 61 by heads 58.

A coupling 62 leads from the recess 31 and has one end of a tube 57', similar to the tube 57, telescoped and adjustably secured therein by a head or cap 58, the other end of which is telescoped and adjustably secured in one end of an L-shaped tube or coupling 63 by a head or cap 58'. The other end of coupling 60 63 has one end of a second tube 57' telescoped and adjustably secured therein by a head or cap 58', the other end of the second tube 57' being telescoped and adjustably secured in a coupling tube 56' connected with 65 the auxiliary inlet 53.

An opening of the valve plug 54 permits the gas to flow from the stringer 16 through the outlet 52 to the recess 42, thence into the interior of the valve member 32, through ports 64 therein, through ports 33 and 34, if 70 the same are in alignment, into the interior of the housing 29, thence into the recess 31, through tubes 62, 57', 63, 57' and 56', the inlet port 53, manifold 18 and thence to the burner or burners 15.

In the event the member 21 is so expanded that ports 33 and 34 are disaligned, a minimum flame is maintained at the burner 15 by gas flowing from recess 42 to recess 31 through a by-pass communicating with 80 said recesses at 65 and 65', respectively. A needle valve 66 having an adjusting screw 67 positioned exteriorly of the base member facilitates the regulation of the volume of gas supplied the burner through the by-pass. 85

The valve member 32 is normally stationary and the valve member 27 is rotated by the expansion and contraction of member 21, to align and disalign the ports 33 and 34 to maintain a flame at the burner sufficient to 90 keep the oven temperature at any predetermined degree which may be set by adjusting the normally stationary valve member 32. Valve member 32 is rotated to any desired position of adjustment by a setting screw 68 95 threaded in a lug or ear 69 on the base 30 and having its inner end abutting a projection or lug 70 formed on the collar member 44, said screw being provided with a knob or adjusting wheel 71 on its outer end. 100 The lug 70 is yieldably maintained in engagement with the inner end of the screw 68 by a spring pressed plunger 72, mounted in the bore of a lug or ear 73 carried by the base 30 diametrically opposite ear 69, between 105 which and a removable cap 75 a spring 74 is confined. The spring pressed plunger 72 in addition to maintaining the lug 70 and the screw 68 in engagement at all times maintains all play or lost motion to one side 110 to thus increase the accuracy of the instrument.

The knob 71 is readily adjustably secured to the screw shaft 68 by a set screw 71' and carries a cylindrical dial or disc 76 provided 115 on its periphery with two sets of figures 77 and 78, see Figure 4, for artificial and natural gas, respectively. To prevent confusion, a shield member 79 is provided which is movable to cover either one of said sets of figures. As is well known in the art, natural gas has a higher B. t. u. than artificial gas, thus requiring a lower volume of gas to maintain a set degree of heat in the oven when natural gas is used and a greater 120 volume to maintain any set degree of heat when artificial gas is required. For this reason the compound dial is employed and the shield 79 moved to cover up the artificial reading when the device is used for natural 125 130

gas, and vice versa. But one turn of the knob 71 is required to operate the instrument from minimum to maximum heat and the dial carries a stop 72' which cooperates with a stop 73' carried by the base member to prevent rotation of the knob more than one turn.

Three means are provided for setting the instrument after the same has been applied to a stove, one, the connecting member 37, which is preferably in the form of an adjustable clamp, another the collar member 44 and the other the set screw 71'. After the instrument has been applied to the oven, the burner is ignited and after the oven has become heated a thermometer reading is taken. Assume the thermometer reading to be three hundred degrees, either the connecting member 37 may be loosened and the knob 71 rotated to align the designation "300" with a pointer 80 carried by the base member and the connecting member then made fast again; the binding screw 47 of the collar member loosened and the knob 71 rotated to align the designation "300" with the pointer 80 and the screw 47 then turned to make the collar member fast to the screw shaft 68, or the set screw 71' loosen and the knob 71 rotated to align the designation "300" with the pointer 80 and the set screw then tightened to make the knob 71 and its dial fast to the screw shaft 68. All of these adjustments are located exteriorly of the oven out of the range of the oven heat and are made under atmospheric conditions rendering them absolutely accurate.

As an added factor of safety against extinction of the burner, a pilot is provided, as best illustrated in Figure 6. The pilot comprises a tube 85, the outer end of which is connected with the coupling 60, as at 85', and the inner end of which is in the form of a pilot tip 81, preferably constructed of Monel, or other similar metal. The pilot tip has an orifice 87 therein at which a pilot flame burns and the size of the pilot flame is adjustable from the front of the oven by a knob 82 from which a flexible shaft 83 leads having a threaded enlargement 84 on its inner end in threaded engagement with the pilot tip. An extension or needle valve member 86 of Monel or other similar metal projects from the enlargement 84 to the orifice whereby the area of the orifice may be readily adjusted to regulate the size of the pilot flame. The enlargement 84 is longitudinally grooved to permit the flow of gas thereby and the adjusting of the orifice opening by the means illustrated insures the maintenance of the proper pressure at the pilot and prevents a variance in the pilot in the event the shaft 83 is effected by temperature changes as its contraction and expansion is rearwardly of the needle valve member 86.

The upper end of the valve structure proper and the outer ends of the members 21 and 36 are preferably enclosed in a housing 88 and the outer-most portion of said housing has a flat surface inclined with respect to the perpendicular and provided with various figures representing the degrees of heat to the side which is delineated the use for which the oven is adapted at such degrees to assist the operator in setting the device. As for example, should the operator desire to set the oven for baking bread, a glance at the top of the housing 88, discloses that "400" degrees is the temperature required and the knob 71 is rotated to align the "400" degree designation of the dial 76 with the pointer 80.

With the oven thus set for "400" degrees, the gas cock 17 is opened and the burner 15 ignited. The oven being practically cold and the member 21 fully contracted ports 33 and 34 are in full alignment and the burner 15 supplied with the volume of gas necessary to burn at full maintenance. As the temperature of the oven approaches "400" degrees, the member 21 rotates, the valve member 27 through the neutral member 36 gradually closing the opening of ports 33 and 34, thus diminishing the supply of fuel to the burner in proportion to the increase in the temperature of the oven.

To insure the instant response of the instrument to any slight variation in the temperature of the oven the members 21 and 36 are preferably tubular, having their rear ends open to the atmosphere and their forward ends provided with relatively small openings 89 and 90, respectively, permitting the constant passage of air therethrough. The circulation through the members 21 and 36 is from the rear to the front, as the openings at the rear are of a greater area than those at the front. The circulation of air through the member 21 is accelerated by temperature changes taking place within the oven. The air passing through member 36 assists in maintaining it at a constant temperature and the air passing through the member 21 insures its instant response to any drop in temperature in the oven, as will be readily apparent.

This construction absolutely eliminates the use of springs against which a thermostatic member must work, as is the case in the majority of thermostatic oven heat regulators now on the market and eliminates a valve member in which the force of gravity must be contended with. Furthermore the gas is at all times kept out of the oven.

In Figure 10 a slightly modified construction is illustrated in which the members 27 and 32 vertically reciprocate instead of rotate. The setting of the device is accomplished by the screw 68 engaging against one arm 91 of a bell crank lever 92 pivotally

mounted, as at 93, to the base member, the influenced by the heat of the oven, means other arm 93 of which is pivotally connected with the lower end of the member 32, as at 94. The member 32 in this embodiment 5 of my invention, is normally urged outwardly of the base member by a spring 95 confined between a flange 96 on the lower end thereof and the wall of the base member to maintain the bell crank arm 91 in constant engagement with the inner end of the screw 68.

In this form of my invention, the member 36 converts the contraction and expansion of member 27 into reciprocal movement by 15 having its end 38 pivotally connected, as at 97, with one arm of a bell crank lever 98 pivoted, as at 99, to the cap 52. The other arm of the bell crank is pivotally connected, as at 100, with the upper end of the trunnion 20 26 which is slidably extended through the cap member 25. As the operation of this form of my invention is substantially identical with that illustrated in Figures 1 to 8, inclusive, further description thereof is 25 deemed unnecessary.

The stringer 16 extends beyond the vertical plane of the oven front and the instrument being inwardly of an imaginary line drawn perpendicularly through the outermost portion of the stringer. As a result, 30 it is unnecessary to make special provision in the crating of the stoves for shipment, thus effecting an economy in material and labor in the crating and facilitating the 35 general handling of the stove.

Furthermore, the control of the gas flowing to the oven burner 15 being directly from the gas cock 17 eliminates special fittings and long lengths of pipe, producing 40 an economy in material and labor in the manufacture and application of the control and materially simplifying its installation, inasmuch as it is only necessary to provide a small aperture in the frame 13 and in the 45 rear oven wall and replace the conventional gas cock of the oven burner with the special gas cock illustrated.

The telescoping and adjustable tubes 57 and 57' make it possible to apply the instrument to either right or left hand stoves without any change in their construction and provide for universal adjustments laterally and vertically and at various angles, 50 eliminating the necessity of providing means to insure positive truing of the various parts during installation.

What I claim as my invention is:

1. In a device of the character described including an oven having a substantially rigid frame at one side and a burner for heating the interior thereof, means for regulating the flow of fuel to the burner in proportion to the temperature of said oven and including a member having a relatively high co-efficient of expansion and adapted to be

connecting one end of said member with said rigid oven frame, the other end of said member being passed outwardly of the oven, a second member having a relatively low co-efficient of expansion and positioned in a neutral zone out of the influence of the heat of the oven, means connecting the second member with the first-mentioned member, a control valve for regulating the flow of fuel to the oven burner, and a connection between said control valve and said second member whereby expansion of said first-mentioned member decreases the flow of fuel to the burner and contraction of said first-mentioned member increases the flow of fuel to said burner.

2. In a device of the character described including an oven having a substantially rigid frame at one side and a burner for heating the interior thereof, means for regulating the flow of fuel to the burner in proportion to the temperature of said oven and including a member having a relatively high co-efficient of expansion and adapted to be influenced by the heat of the oven, means connecting one end of said member with said rigid oven frame, the other end of said member being passed outwardly of the oven, a second member having a relatively low co-efficient of expansion and positioned in a neutral zone out of the influence of the heat of the oven, means adjustably connecting the second member with the first-mentioned member, a control valve for regulating the flow of fuel to the oven burner, and a connection between said control valve and said second member whereby expansion of said first-mentioned member decreases the flow of fuel to the burner and contraction of said first-mentioned member increases the flow of fuel to said burner.

3. In a device of the character described including an oven having a substantially rigid frame at one side and a burner for heating the interior thereof, means for regulating the flow of fuel to the burner in proportion to the temperature of said oven and including a member having a relatively high co-efficient of expansion and adapted to be influenced by the oven heat, means connecting one end of said member with said rigid oven frame, the other end of said member being passed outwardly of the oven, a second member having a relatively low co-efficient of expansion and positioned in a neutral zone out of the influence of the heat of the oven, means connecting one end of said second member with the adjacent end of the first-mentioned member, a control valve for regulating the flow of fuel to the oven burner, means securing said control valve to said oven rigid frame, and a connection between the control valve and said second member whereby expansion of said

first-mentioned member decreases the flow of fuel to the burner and contraction of said first-mentioned member increases the flow of fuel to said burner.

5. 4. In an appliance of the character described including an oven, a burner for the oven and a valve for regulating the flow of fuel to the burner, a thermostatic member for actuating said valve and including a tubular member having a relatively high coefficient of expansion and positioned within the interior of said oven, and means permitting the circulation of air through said member.

15. 5. In an appliance of the character described including an oven, a burner therefor and a valve for regulating the flow of fuel to the burner, a thermostatic member for actuating said valve and including a tubular member having a relatively high coefficient of expansion and positioned within the interior of said oven, and means permitting the circulation of air from the exterior of said oven through said tube whereby said tube member instantly responds to a fall in the temperature of the oven.

6. In an appliance of the character described including an oven, a burner therefor and a valve for regulating the flow of fuel to the burner, a thermostatic member for actuating said valve and including a tubular member having a relatively high coefficient of expansion and positioned within the interior of the oven, means permitting the circulation of air through said member, a second tubular member mounted exteriorly of the oven and having a relatively low coefficient of expansion, means connecting the second member with the first-mentioned member, means connecting said second member with the burner control valve, and means permitting the circulation of air through said second member whereby the temperature thereof is maintained substantially constant.

7. In a device of the character described including an oven and a burner for heating the same, a valve member for controlling the flow of fuel to said burner, a member disposed within the oven and having a relatively high coefficient of expansion, a second member disposed exteriorly of the oven and having a relatively low coefficient of expansion, means connecting said members whereby expansion and contraction of said first member shifts both of said members in the same plane, and a connection between said second member and the control valve whereby movement of said second member actuates the control valve.

8. In a device of the character described including an oven and a burner for heating the same, a valve member for controlling the flow of fuel to said burner, a member dis-

posed within the oven and having a relatively high coefficient of expansion, a second member disposed exteriorly of the oven and having a relatively low coefficient of expansion, means connecting said members whereby expansion and contraction of said first member shifts the second member, a connection between said second member and the control valve whereby movement of said second member actuates the control valve, and means permitting the circulation of air through said second member whereby the same is maintained at a substantially constant temperature.

9. A device of the character described, comprising an oven, a burner therefor, a source of fuel, a pair of freely rotatable telescoping tubular valve members, a housing enclosing said tubular members, ports in said tube members adapted to register, means connecting the interior of one member with the source of fuel and the interior of the housing with the burner, whereby the volume of fuel supplied the burner is controlled by said ports, and means actuated by a rise or fall in the temperature of the oven to open and close said ports to regulate the flow of fuel to said burner.

10. A device of the character described, comprising an oven, a burner therefor, a source of fuel, a pair of telescoping tubular valve members, a housing enclosing said tubular members, ports in said tubular members adapted to register, means connecting the interior of one member with the source of fuel and the interior of the housing with the burner, whereby the volume of fuel supplied the burner is controlled by said ports, means actuated by a rise or fall in the temperature of the oven to move one of said telescoping members and open or close said ports to control the volume of fuel supplied the burner through said ports, and manually actuated means for adjusting the other of said telescoping members.

11. In an appliance of the character described including an oven, a burner and a fuel supply therefor, means for adjustably connecting the burner with its fuel supply and including a valve member, a member disposed in the oven and having a relatively high coefficient of expansion, the forward end of said member being projected through the oven front wall and the rear end of said member being projected through the rear wall of the oven, means connecting the forward end of said member with the valve member, a second member positioned exteriorly of the oven and having a relatively low coefficient of expansion, means connecting the rear end of said second member with the rear end of the first member, and means connecting the forward end of said second member with the valve member.

whereby expansion or contraction of said first-mentioned member shifts the second member and actuates the valve member.

12. In a gas stove having an oven, a burner for the oven and a gas cock for connecting the same to a gas supply, said gas cock having two inlets and two outlet ports, one outlet port being connected with the supply and one outlet port being connected with the burner, an automatic valve actuated by a rise and fall of temperature within the oven, and means connecting the other inlet and outlet ports with the valve whereby the gas flows from the supply through the gas cock, through the control valve, and back to the gas cock before flowing to the burner.

13. A device of the character described comprising an oven, a burner therefor, a source of fuel, a pair of freely rotatable and telescoping tubular valve members, a housing enclosing said members, ports in said tube members adapted to register for the passage of fuel therethrough, means connecting the interior of one member with the source of fuel and the interior of the housing with the burner whereby the volume of fuel supplied to the burner is controlled

by the ports, means for manually moving one valve member with respect to the other, and automatic means actuated by a rise and fall of the temperature within the oven for moving the second valve member with respect to the first to open and close said ports.

14. A device of the character described including an oven, a burner therefor, a source of fuel supply and a valve for connecting the burner with the supply, a by-pass through which the fuel pass prior to its passage from the valve to the burner, a valve positioned within said by-pass for controlling the flow of fuel to the burner, said valve including a stationary casing having therein a manually adjusted valve portion, a second valve portion fitting over the first said valve portion, ports in said valve portions adapted to register for the passage of fuel therethrough, and automatic means positioned within the oven and connecting to one of said valve portions for controlling the flow of fuel to the burner on the rise and fall of the temperature within the oven.

In testimony whereof I affix my signature.
EMIL L. CLAUS.
